HYDRAULIC TAPPETS

Paul F. Bergmann, Sr., North Muskegon, Mich., assignor to Johnson Products Incorporated, Muskegon, Mich., a corporation of Michigan

Application January 27, 1958, Serial No. 711,221

10 Claims. (Cl. 123—90)

This invention relates to tappets and more particularly to hydraulic tappets for use with internal combustion engines.

The efficient operation of internal combustion engines requires that the engine valves be opened and closed at specific times in the combustion cycle of the engine. Timing cams are normally used for this purpose. The timing cams are adapted to operate the engine valves through a valve actuating mechanism which is engaged with the valves. The valve actuating mechanism usually includes several parts each of which is subject to expansion and contraction, under changing engine temperatures, and to wear. Consequently, there is also required to be some means for automatically compensating for any change in the overall length of the valve actuating parts. Otherwise the timing pattern set by the cams is not always the same.

Hydraulic tappets have been accepted as a suitable means of compensating for any changes in the effective length of valve actuating mechanism. Such tappets are normally disposed between the timing cam and the valve actuating mechanism. When engine temperatures rise and the valve actuating parts expand, the effective length of the tappet decreases accordingly. When the engine temperatures decrease and the valve actuating parts contract, or when the parts become worn, the effective length of the tappet increases accordingly.

Conventionally known hydraulic tappets operate on the principle of transmitting the energy of the actuating cam through hydraulic fluid trapped in a chamber behind a plunger member. During each revolution of the actuating cam small quantities of hydraulic fluid are permitted to escape from the chamber and the plunger is allowed to adjust its relative position in the tappet body. If there has been an increase in the effective length of the valve train parts the plunger seeks a position lower within the tappet body. If there has been a decrease in the effective length of the valve train parts, or no change, a plunger return spring will return the plunger to a higher relative position in the tappet body, or to its original position, as the case may be.

The escape of hydraulic fluid from the pressure chamber of conventionally known tappets is referred to as "leakdown" and occurs between the plunger and tappet body walls. Leakdown is controlled solely by the fit of the plunger within the tappet body member. This requires that the plungers and tappet body members be precision machined, carefully sorted, and selectively fitted together. Clearance between the two parts is generally required to be held to within .0002 to .00023 of an inch. Even with considerable care in the selective assembly of these tappet parts a certain percentage of the assembled tappets are below standards. Such tappets have a leakdown which is either too fast or too slow. As a result of the tappet must be refitted and reassembled or it will not operate satisfactorily. The necessity for controlling leakdown and the complexity of the manufacture and as-

2

sembly of tappets to include such a feature greatly increases tappet costs.

The hydraulic tappet of this invention is not dependent upon the control of leakdown between the plunger and tappet body members in the manner of conventionally known tappets. Instead, an oil sealing member, and a relief are provided within the tappet to control the escape of hydraulic fluid from the pressure chamber space after each stroke. This permits a much larger clearance between the plunger and tappet body members. The larger clearance in turn eliminates the precision machining, sorting and selective assembly operations previously required. There is less chance for operational failure resulting from minute particles in the hydraulic fluid being caught in the annular clearance space between the plunger and tappet body members. The proposed seal and valve mechanism is less expensive to provide, more dependable in operation and assures a more precise control of the valve train adjustment.

20 The particular valve arrangement of this invention is disposed between the plunger member and push rod seat member of a tappet. The valve includes a resilient member seated against an end face of the push rod seat member. The resilient member has a valve seat facing engaging the upper end of the plunger member. The resilient member is exposed to the fluid pressure within the pressure chamber spaces of the tappet. When the fluid pressure is great enough the resilient member is compressed, separated from the plunger member, and fluid is allowed to escape the pressure chamber spaces.

25 The particular relief valve proposed has other decided advantages. These include means of positively locating the valve relative to the push rod seat member and a means of sealing against fluid leakage past the valve member. When the resilient member is under compression it is radially expanded into secure engagement with the push rod seat member and into fluid pressure sealing engagement with the tappet body walls.

30 The disclosed relief valve operates to provide tappet adjustment at a different time in the engine valve operating cycle than is the case with conventional hydraulic tappets. In conventional hydraulic tappets leakdown occurs during the raising and lowering of the tappet on the timing cam. Since the conditions causing leakdown vary during the operation of the tappet the escape of hydraulic fluid permitted must be in accord with the most extreme conditions in order to be assured an adequate adjustment when needed. The tappet of this invention adjusts its length after the engine valve is closed and when the tappet has returned to the base circle of the timing cam. The adjustment is only such as is required under the conditions at the time of adjustment; which is when the tappet and valve train mechanism are inoperative and the best measure of the adjustment required can be made.

35 55 These and other advantages of the disclosed hydraulic tappet will be more apparent to those familiar with hydraulic tappets upon a reading of the following specification and an examination of the accompanying drawings.

In the drawings:

Fig. 1 is a cross sectional view of the proposed hydraulic tappet in one operational position.

Fig. 2 is a cross sectional view of the same hydraulic tappet in another operational position.

Fig. 3 is a cross sectional view of the proposed tappet taken in the plane of line III—III in Fig. 2 and looking in the direction of the arrows to show the unseated pressure chamber relief valve.

In executing the objects and purposes of this invention a hollow tappet body is provided that is closed at one end. A hollow plunger is disposed within the tappet body and forms a pressure chamber with the blind end of the tappet body. A push rod seat is received within the

tappet body above the plunger. The hollow interior of the plunger forms a hydraulic fluid reservoir. The reservoir of the tappet is in free communication with a source of hydraulic fluid received through passageways formed in the push rod seat and through the tappet body. A check valve is provided in the lower end of the plunger for admitting hydraulic fluid from the reservoir into the pressure chamber when the supply in the latter falls below operating requirements. The pressure chamber is to be considered as inclusive of the space between the plunger and the tappet body side walls and is closed by a relief valve arrangement provided between the push rod seat and the end of the plunger adjacent thereto. The hydraulic fluid pressure in the pressure chamber spaces provides an opening force against the relief valve to permit the flow of hydraulic fluid from the pressure chamber into the reservoir under certain operating conditions which will be described.

Referring specifically to the drawings, the proposed hydraulic tappet 1 includes a tappet body 2 which is reciprocally seated within a housing 3, such as would be provided by an engine block. The housing 3 has an oil supply passageway 4 communicating with a wide, external and circumferential groove 5 formed about the tappet body 2. The length of the groove 5 assures communication between the groove and the passage 4 as the tappet body reciprocates within the housing. An aperture 6 within groove 5 provides an access for hydraulic fluid into the tappet body.

The tappet body 2 is closed at one end, which is the end engaged by a timing cam 7, and is open at the other end. A plunger 10 is slidably disposed within the tappet body 2. The plunger 10 is hollow and forms a hydraulic fluid reservoir 11. A passage 12 is formed through the lower end of the plunger to provide a means of communication between the reservoir 11 and a pressure chamber 13 formed between the end of the plunger and the blind end of the tappet body. A check valve 14 is biased, by a lightweight spring 15, into closed position against the end of the plunger and over the passage 12. The check valve 14 prevents communication between the fluid reservoir 11 and the pressure chamber 13 except when the pressure in the reservoir exceeds that in the pressure chamber sufficient to overcome the small tension exerted by the spring 15.

The lower end of the check valve spring 15 bears against a cap 16. The cap 16 is engaged to the end of the plunger 10 about wall 19 formed on the lower end thereof. An aperture 17 in the terminal end of the cap and apertures 18 provided in the sides thereof permit the flow of hydraulic fluid about the cap. The plunger is biased away from the closed end of the tappet body by a plunger return spring 20.

The fit of the plunger 10 within the tappet body 2 is such that the pressure chamber 13 is to be considered to extend to the top edge of the plunger and to be inclusive of the annular space 21 between the outer walls of the plunger and the inner walls of the tappet body. This clearance is not sufficient to allow an unrestricted flow of the hydraulic fluid between the plunger and tappet body walls. However, it is sufficient to permit a near uniform fluid pressure condition to be built up between the pressure chamber and about the plunger in the course of tappet operation. In a tappet constructed according to this invention, the clearance between the plunger and the inside surface of the tappet body may be as much as .005 or .006 of an inch as compared to the 0.0002-0.00023 of an inch clearance permissible in conventional tappets.

The upper end of the plunger 10 is machined to form a smooth and accurate valve seat 26 which cooperates with the relief valve 27 of this invention to close off the end of the pressure chamber 13 extending about the plunger. The relief valve 27 comprises an annular member 28 of a resilient material such as neoprene suitable for use in

the presence of hydraulic fluids and related liquid hydrocarbons. A thin metallic annular disc 29 is engaged to one face of the resilient member 28 to provide a better surface for the closing of the valve against the valve seat 26 of the plunger. The disc member 29 has a smaller outer diameter and a larger inner diameter than the resilient member 28. The disc member is disposed to prevent distortion of the resilient member 28 under high pressure conditions within the pressure chamber 13, which, as will be explained, are used to activate the valve.

The valve member 27 is engaged with the push rod seat member 30 which is slidably disposed within the tappet housing above the plunger 10. The rod seat member 30 has a generally spherical depression 31 formed within the upper surface thereof for the reception of the end of a push rod 32 which forms part of the valve train linkage. The peripheral surface of the push rod seat member 30 is formed to provide a sliding and liquid restraining seal with the inner walls of the tappet body 2. An annular passage or groove 34 is formed about the push rod seat and communicates through the opening 6 in the tappet body and the annular groove 5 with the oil supply passage 4. Passages 36 and 37 formed through the push rod seat member and in communication with groove 34 provides the means of communication for hydraulic fluid to the reservoir 11. Passage 37 extends through the spherical seat 31 as a manufacturing aid in forming the seat. However the passage is sealed against fluid leakage by the engagement of the end of the push rod 32 therein.

The end of the push rod seat 30 next adjacent the plunger is reduced in diameter substantially below that of the internal diameter of the plunger member. This forms a boss 40. An annular groove 41 is provided around the boss and the compressible valve member 28 is received in this groove. The internal diameter of the resilient valve member 28 is smaller than the head portion of the boss 40. Thus, the valve member is assured a tight fit thereon. The disc member 29 of the valve

40 will be noted to have an internal diameter greater than that of the head of the boss 40 thus eliminating interference between the two parts.

The compressible member 28 of the valve 27 is backed by a radially disposed end wall 50 of the rod seat member 30. Any pressures imposed upon the lower face of valve 27, tending to lift the disc part from the valve seat 26, will compress the valve member 28. This causes the resilient material to flow or expand radially outward and inward, locking the valve into tighter engagement with the push rod seat member 30 and into tighter sealing engagement with the walls of the tappet body member 2 engaged thereby. Separation of the disc member 29 from the valve seat 26 provides a return or bleed passage for the escape of hydraulic fluid from the pressure chamber 13 back into the reservoir 11. Fig. 2 shows such a passage with the separation highly exaggerated for illustration purposes.

The entire internal structure of the tappet just described is prevented from disassembly from the tappet body 2 by a snap ring 60 seated in a suitable groove 62 provided in the inner wall of the tappet body 2 adjacent its open end.

Operation

65 For the purposes of describing the operation of this invention, it is assumed that the tappet is in the position illustrated in Fig. 1 with the eccentric portion of the cam 7 about to be engaged with the lower end of the tappet body. The valve train mechanism has not been shown because it is considered to be of such conventional design as to be readily understood and its relation to parts shown to be adequately known, without illustration.

66 The forces within the tappet are substantially in balance. The plunger return spring 20 holds the plunger engaged with the relief valve member 27 and the relief

valve 27 against the push rod seat member 30. The push rod 32 is backed by the resistance of the engine valve spring to prevent further upward movement of the push rod seat member. The reservoir chamber 11, pressure chamber 13, and annular pressure chamber space 21 are filled with hydraulic fluid at substantially equal pressures.

When the eccentric portion of cam 7 engages the base 39 of the tappet body 2, the tappet body is lifted. The plunger 10 is also raised due to the incompressible nature of the hydraulic fluid trapped in the pressure chamber 13. The plunger member 10 acts against the relief valve 27 in its effort to lift the push rod seat member 30. The resistance of the engine valve spring to compression is greater than that of the compressible member 28 of the relief valve. Consequently, the member 28 is compressed a few thousandths of an inch in the first effort of the plunger to lift the rod seat member 30.

The compressible member 28 is caused to spread radially and to be forced into more secure engagement with the push rod seat member, within groove 41. The resilient member 28 is also forced into tighter fluid sealing engagement with the internal walls of the tappet body member.

During the remainder of the rise of the tappet body 2, under the influence of the timing cam 7, the push rod seat member 30 transmits the cam lift force to the push rod 32 in the effort to lift the engine valve against the resistance of the engine valve spring.

The increased resistance of the engine valve spring to compression, in allowing the engine valve to be opened further, produces an increased fluid pressure condition in the pressure chamber 13. The increasing fluid pressure condition in chamber 13 seeks to equalize itself in the annular pressure chamber space 21 about the plunger. However, the restrictive character of the annular space 21 produces a pressure gradient between the upper end of the plunger, near the relief valve, and the lower end thereof, which opens into the pressure chamber space 13.

During the rise of the tappet the pressure build up in chamber 13 will tend to raise the pressure condition in space 21, next adjacent to the relief valve, to the same pressure level. As the tappet passes the crest of the cam 7 and begins to fall back, the resistance of the engine valve spring decreases. The pressure condition in chamber 13 also begins to fall off accordingly. During the return of the tappet to the base circle of cam 7 the pressure condition in chamber 13 will fall below that at the upper end of the annular space 21 next adjacent the relief valve 27.

At the return of the tappet to the base circle of cam 7, the force of the engine valve spring will be withdrawn from the rod seat member 30. This happens when the engine valve closes. The resilient member 28 of the relief valve 27 will still be compressed, just as it was when the tappet first started its rise and as it remained throughout the rise and fall of the tappet.

At the moment the engine valve spring force is withdrawn from the rod seat member 30 the unit pressure in the pressure chamber space 13 falls off. Accordingly, there exists a greater unit pressure at the upper end of the annular pressure chamber space 21, near the relief valve 27, than exists below the plunger.

The unit pressure condition near the upper end of the annular pressure chamber space 21 is sufficient to hold the resilient member 28 compressed as the tappet body member 2 returns to the base circle of the timing cam 7. The plunger 10 travels with the tappet body member 2, on the return to the base circle of the cam, just as it did during the initial rise of the tappet and compression of the resilient member 28 of the relief valve. Thus the greater pressure condition built up next adjacent the relief valve 27, during the operation of the tappet, and unable to be dissipated as fast as in the pressure chamber space 13, serves to open the relief valve 27.

When the relief valve 27 opens a small amount of hy-

draulic fluid is allowed to escape from the pressure chamber space 21 into the reservoir 11. To the extent that this depletes the supply of hydraulic fluid in the pressure chamber spaces, the plunger member 10 may be axially adjusted within the tappet body member.

If the valve actuating members have increased their length, due to expansion resulting from increased engine temperature conditions or the like, then the push rod member 30 will have been returned to a lower relative position in the tappet body member 2 before the relief valve 27 opened. As a result, the relief valve is permitted to open later and not as wide as if there had been no growth in the valve train parts. However, the opening permitted the valve 27 is sufficient to take care of the incremental growth of the parts, during one cycle of the tappet operation, and still vent the pressure chamber spaces to the reservoir chamber. The plunger member 10 will retain its lower position, due to the fluid loss from the pressure chamber spaces, and the necessary adjustment of the 20 tappet will have been made.

When the valve train parts have contracted, shortening their effective length, the valve opening occurs sooner. The plunger return spring 20 adjusts the plunger to a higher relative position in the tappet body member, accordingly, and the check valve 14 opens as required to replenish fluid in the pressure chamber 13 and to balance the condition therein with that in the reservoir 11.

In discussing the operation of the disclosed tappet, it is to be remembered that these tappets operate at high 30 speeds and that the adjustments involved and the fluid exchange to effect the adjustments are all incremental measurements. The disclosed tappets are of an actual size much smaller than is shown by the illustrations and the valve opening, clearance spaces, etc., are required to be exaggerated for illustration purposes. Also, it should be said that while the theory of operation of this tappet is considered to be as has been described, that the tappet 35 may operate differently. The momentum of the valve train parts, including push rod, push rod seat, and plunger 40 cause an increase in pressure in chamber 13 and space 21 at the instant that downward travel of these parts is stopped by the cam. This pressure would be sufficient to separate relief valve 27 from surface 26 to permit a leakage of fluid from the pressure chamber into the reservoir, 45 thus allowing the plunger to adjust itself to the proper position in readiness for the next opening of the engine valve. However, tests have proven that the results disclosed are obtained by tappets made in accord with the teachings of this invention, both in the disclosed form 50 and with certain modifications.

Therefore, and in conclusion, while a preferred embodiment of this invention has been described it will be understood that other modifications and improvements 55 may be made thereto. Such of these modifications and improvements as incorporate the principles of this invention are to be considered as included in the herein-after appended claims unless these claims by their language expressly state otherwise.

I claim:

60 1. In a hydraulic tappet comprising a blind end hollow tappet body having a plunger member slidably disposed therein and forming a pressure chamber with the blind end thereof, a push rod seat member slidably disposed within said tappet body next adjacent said plunger and forming a reservoir chamber therewith, and a reservoir pressure responsive check valve disposed between said pressure and reservoir chambers at one end of said plunger; pressure responsive means for venting said pressure chamber to allow for the axial adjustment of said plunger relative to said tappet body, and comprising: 65 having said pressure chamber in restricted communication with the annular space between said plunger and said tappet body, valve means disposed between said pressure and reservoir chambers at the other end of said plunger and including a compressible member having a 70 75

noncompressible facing engaged with said plunger, said compressible member yielding axially to a fluid pressure within said pressure chamber less than that required to effect movement of said push rod seat and greater than that required to actuate said plunger for unseating said facing from said plunger and venting said pressure chamber to said reservoir.

2. In a hydraulic tappet comprising a blind end hollow tappet body having a plunger member slidably disposed therein and forming a pressure chamber with the blind end thereof, a push rod seat member slidably disposed within said tappet body next adjacent said plunger and forming a reservoir chamber therewith, and a reservoir pressure responsive check valve disposed between said pressure and reservoir chambers pressure responsive means for venting said pressure chamber to allow for the axial adjustment of said plunger relative to said tappet body, and comprising; said pressure chamber being in restricted communication with the annular space between said tappet body and said plunger, a valve member disposed between said push rod seat and plunger member and engaged with the upper end of said plunger for closing said pressure chamber from said reservoir, said valve member including a fluid responsive compressible member engaged against an end wall of said push rod seat and disposed in sealing engagement between the end of said plunger and said tappet body.

3. In a hydraulic tappet comprising a blind end hollow tappet body having a plunger member slidably disposed therein and forming a pressure chamber with the blind end thereof, a push rod seat member slidably disposed within said tappet body next adjacent said plunger and forming a reservoir chamber therewith, and a reservoir pressure responsive check valve disposed between said pressure and reservoir chambers; pressure responsive means for venting said pressure chamber to allow for the axial adjustment of said plunger relative to said tappet body, and comprising; said pressure chamber extending between said tappet body and said plunger to the upper end of said plunger, a valve member disposed between said rod seat and the upper end of said plunger for closing said pressure chamber, said valve member including a fluid pressure responsive compressible member engaged against an end wall of said push rod seat and having a noncompressible facing seating against the end of said plunger and separating said pressure chamber from said reservoir, said compressible member being disposed in sealing engagement between said push rod seat and tappet body and being axially compressible in response to fluid pressure within said pressure chamber to lift said facing and vent said pressure chamber to said reservoir.

4. In a hydraulic tappet comprising a blind end hollow tappet body having a plunger member slidably disposed therein and forming a pressure chamber with the blind end thereof, a push rod seat member slidably disposed within said tappet body next adjacent said plunger and forming a reservoir chamber therewith, and a reservoir pressure responsive check valve disposed between said pressure and reservoir chambers; pressure responsive means for venting said pressure chamber to allow for the axial adjustment of said plunger relative to said tappet body, and comprising; said pressure chamber being inclusive of the annular space between said plunger and said tappet body, a valve member disposed between said push rod seat and said plunger for closing said pressure chamber and separating said reservoir therefrom, said valve member including an axially and radially compressible member engaged to said push rod seat member adjacent an end wall thereof and disposed in sealing engagement with said tappet body, said compressible member being responsive to the fluid pressure within said pressure chamber and yielding axially to open said valve and vent said pressure chamber to said reservoir.

5. In the hydraulic tappet of claim 4, said push rod

seat member having a boss extending from the end face thereof and an annular groove formed therein, said compressible member being annular and having the inner peripheral edge thereof smaller than said push rod seat part and received within said groove.

6. In a hydraulic tappet comprising a blind end hollow tappet body having a plunger member slidably disposed therein and forming a pressure chamber with the blind end thereof, a push rod seat member slidably disposed within said tappet body next adjacent said plunger and forming a reservoir chamber therewith, and a reservoir pressure responsive check valve disposed between said pressure and reservoir chambers; pressure responsive means for venting said pressure chamber to allow for the axial adjustment of said plunger relative to said tappet body, and comprising; said pressure chamber extending between the peripheral surfaces of said plunger and said tappet body, a valve member disposed between said push rod seat and said plunger and engaging the upper end of said plunger for separating said pressure chamber from said reservoir, said valve member including an axially and radially compressible annular member having one end face thereof engaged with and backed against an end face of said push rod seat member, the inner peripheral edge thereof disposed in sealing engagement with said push rod seat member, and the outer peripheral edge thereof disposed in sealing engagement with said tappet body, said compressible member yielding axially and separating from said plunger in response to fluid pressure within said pressure chamber to vent said pressure chamber to said reservoir.

7. In a hydraulic tappet comprising a blind end hollow tappet body having a plunger member slidably disposed therein and forming a pressure chamber with the blind end thereof, a push rod seat member slidably disposed within said tappet body next adjacent said plunger and forming a reservoir chamber therewith, and a reservoir pressure responsive check valve disposed between said pressure and reservoir chambers; pressure responsive means for venting said pressure chamber to allow for the axial adjustment of said plunger relative to said tappet body, and comprising; said pressure chamber extending peripherally about said plunger to the upper end thereof, a valve member disposed between the adjacent ends of said plunger and said push rod seat member and adapted to close and open communication between said pressure and reservoir chambers, said valve member including an axially compressible and radially yielding member engaged against said push rod seat member and disposed in fluid sealing peripheral engagement with said tappet body and said push rod seat member, said compressible member being responsive to axial pressure imposed by said plunger for yielding radially into fluid pressure sealing engagement with said tappet body and push rod seat member.

8. In a hydraulic tappet comprising a blind end hollow tappet body having a plunger member slidably disposed therein and forming a pressure chamber with the blind end thereof, a push rod seat member slidably disposed within said tappet body next adjacent said plunger and forming a reservoir chamber therewith, and a reservoir pressure responsive check valve disposed between said pressure and reservoir chambers; pressure responsive means for venting said pressure chamber to allow for the axial adjustment of said plunger and push rod members relative to said tappet body, and comprising; said pressure chamber being in restricted communication with the upper end of said plunger, a valve member disposed between the adjacent ends of said plunger and said push rod seat member and for controlling communication between said pressure and reservoir chambers, said valve member including an axially compressible and radially expandible member backed against an end face of said push rod seat member and disposed in fluid sealing peripheral engagement with said tappet body and said

push rod seat member, said compressible member being responsive to axial pressure imposed by said plunger for contracting axially and separating from said plunger to vent said pressure chamber to said reservoir and for expanding radially into fluid pressure sealing engagement with said push rod seat and tappet body to hold such fluid pressure peripheral sealing engagement against fluid pressures in said pressure chamber during the operation of said tappet.

9. In a hydraulic tappet comprising a blind end hollow tappet body having a plunger member slidably disposed therein and forming a pressure chamber with the blind end thereof, a push rod seat member slidably disposed within said tappet body next adjacent said plunger and forming a reservoir chamber therewith, and a reservoir pressure responsive check valve disposed between said pressure and reservoir chambers at one end of said plunger; pressure responsive means for venting said pressure chamber to allow for the axial adjustment of said

plunger relative to said tappet body, and comprising: valve means disposed between said pressure and reservoir chambers at the other end of said plunger, said valve means being responsive to fluid pressure conditions within said pressure chamber for venting said pressure chamber to said reservoir, and means provided by said push rod seat member for retaining said valve means engaged therewith.

10. In the hydraulic tappet provided for by claim 9; said means for retaining said valve member to said push rod seat member comprising a boss formed from the end face of said push rod seat and having an annular groove provided therearound, and said valve means including an inner peripheral portion received and retained in said groove.
